UNITED STATES PATENT OFFICE.

HIRAM T. BUSH, OF DETROIT, MICHIGAN.

DESIGN FOR A HINGE.

SPECIFICATION forming part of Design No. 34,135, dated February 26, 1901.

Application filed February 4, 1901. Serial No. 46,034. Term of patent 7 years.

To all whom it may concern:

Be it known that I, HIRAM T. BUSH, a citizen of the United States, residing at Detroit, in the county of Wayne and State of Michigan, have invented and produced a certain new and original Design for a Hinge, of which the following is a specification, reference being had therein to the accompanying drawings, in which—

10 Figure 1 is a front elevation, and Fig. 2 is a plan.

A and B are two substantially rectangular plates arranged side by side, with parallel adjacent edges spaced from each other. Arranged with its major axis in a plane between these plates is an ovoidal knob comprising two semiovoidal sections C and D, separated by the line a.

15 E and F are necks respectively connecting

the semiovoidal sections with the plates A 20 and B.

The leading feature of the design consists in the arrangement of the ovoidal knob with its major axis in a plane between the adjacent edges of the plates, said knob being divided 25 in two sections by an encircling central line and said semiovoidal sections being connected by necks, respectively, to said plates.

What I claim as my invention is—

The design for a hinge, substantially as 30 herein shown and described.

In testimony whereof I affix my signature in presence of two witnesses.

HIRAM T. BUSH.
